Primary Examiner — Jasmine Mlinarcik

(57) **CLAIM**

The ornamental design for a self supporting grooming device, as shown and described.

DESCRIPTION

FIG. 1 is a top, perspective view of the self supporting grooming device, showing my new design in the open position;

FIG. 2 is a front elevation view thereof;

FIG. 3 is a right side elevation view thereof, the left side being a mirror image thereof;

FIG. 4 is a rear elevation view thereof;

FIG. 5 is a top view thereof;

FIG. 6 is a bottom view thereof;

FIG. 7 is a bottom, perspective view thereof;

FIG. 8 is a top, perspective view thereof; the view showing the design in a partially folded position; the view showing the material of shoulder portion flat; and,

FIG. 9 is a top, perspective view thereof; the view showing the design in a closed position.

The broken lines depict portions of the self supporting grooming device that form no part of the claimed design.

1 Claim, 9 Drawing Sheets
